UNITED STATES PATENT OFFICE

137,262

DESIGN FOR A FOOD CONTAINER

Vera D. Hiemenz, Pacific Palisades, Calif.

Application October 6, 1943, Serial No. 111,279

Term of patent 14 years

To all whom it may concern:

Be it known that I, Vera D. Hiemenz, a citizen of the United States, residing at Pacific Palisades, in the county of Los Angeles and State of California, have invented a new, original, and ornamental Design for a Food Container, of which the following is a specification; reference being had to the accompanying drawing, forming a part thereof.

The single figure in the drawing is a perspective view of a food container, showing my new design.

I claim:

The ornamental design for a food container, as shown.

VERA D. HIEMENZ.
